United States Patent Office.

HIRAM P. WETMORE, OF ELIZABETH, NEW JERSEY.

Design No. 4,938, dated May 23, 1871.

DESIGN FOR DRAWERS.

The Schedule referred to in these Letters Patent and making part of the same.

I, HIRAM P. WETMORE, of Elizabeth, in the county of Essex, State of New Jersey, have invented and produced a new and original Design for Drawers, of which the following is a specification.

I insert a gore at the back and one on each hip, extending down in a tapering form and terminating in a point.

The gores are of different colors from the body of the drawers; as, for example, the body being white, the gores are a bright scarlet, so as to appear very conspicuously. They give an enlivening and brilliant effect to the appearance of the goods.

The gores taper, not uniformly, but more rapidly near their upper ends—in other words, the sides of the gores are formed with a curve.

The nature of my design is fully represented in the accompanying drawing, to which reference is made.

Figure 1 is a front view;
Figure 2, a back view; and
Figure 3 a side view, partially folded.

Claim.

I claim as my invention—
The design for drawers, as shown and described.
In testimony whereof I have hereunto set my name
in presence of two subscribing witnesses.

H. P. WETMORE.

Witnesses:

THOMAS D. STETSON,
C. C. LIVINGS.
